CLAIM

The ornamental design for a container with label and golf balls, as shown and described.

DESCRIPTION

FIG. 1 is a front elevational view of the container with label and golf balls showing my new design;

FIG. 2 is a side elevational view thereof;

FIG. 3 is a back elevational view thereof;

FIG. 4 is a top plan view thereof; and,

FIG. 5 is a bottom plan view thereof.

The stipple shading on the label area indicates a textured surface.
